CATHODE RAY TUBE GUN ASSEMBLY
 John William Snyder, Hatfield, Pa., assignor, by mesne assignments, to Philco Corporation, Philadelphia, Pa., a corporation of Delaware
 Filed Oct. 24, 1961, Ser. No. 147,270
 8 Claims. (Cl. 313—256)

This invention relates generally to cathode-ray tubes, and more particularly to improvements in cathode ray tube gun assemblies. The invention, while applicable in its broader aspect to cathode ray tubes generally, will be described and illustrated in relation to constricted neck tubes, where it has special utility.

In the assembly of electron guns for cathode ray tubes and the like, it has been the practice to bind the metal electrode elements by insulators which are viscous at the time of application, but which later solidify into rigid insulating members. Attachment, or binding, of the metal parts to the insulating members is facilitated by means of axially aligned studs or brackets attached to and extending radially from the aforementioned metal parts. The insulating members have comprised parallelly disposed glass rods heated to a suitable viscous state and applied individually to one radially extending axially aligned set of studs at a time. In the assembly of electrode elements of gun structure comprising, for example, a plurality of glass rods, the rods must be heated individually, in succession, in order to complete the assembly. In a high production volume of gun structures in which such electrode assemblies are utilized, a separate heating and cooling operation in attaching each insulator represents a considerable time factor in the overall production rate.

Also there has been increased demand for more compact television picture tubes of large fluorescent screen area. Efforts toward achieving compactness by reducing tube depth have involved increasing the electron beam deflection angle and reducing the length and diameter of the tube neck within which the electron gun is disposed. As to reduction of the dimensions of the tube neck, difficulties have been encountered in that the above described glass rod-supported gun structure does not lend itself to a reduction in diameter to the extent required. The present invention is directed primarily to overcoming these difficulties.

It is therefore a general objective of the invention to provide a novel electron gun structure permitting reduction in the dimensions of the neck of a cathode ray tube through a unique arrangement of insulating and support structure. This objective the invention has in common with the invention described and claimed in the copending application of Samuel H. Borman entitled "Cathode Ray Tube Gun Structure," Serial No. 146,952, filed October 23, 1961, and assigned to the assignee of the present invention.

It is a further general objective of the invention to provide both a method of and means for effecting highly accurate assembly of the elements of electron gun structure in a minimum of space.

It is also an objective of the invention to provide a simplified and improved assembly of axially aligned tubular metallic parts, such for example as electrode elements of a cathode ray tube gun structure of the type disclosed in the copending Borman application, and further to provide a rapid, economical, and a highly accurate assembly of the parts in the desired rigid predetermined alignment and in the necessary insulated spaced relation.

The invention is featured by the provision of an electron gun which is very simple yet very rigid in construction. It is an additional feature of the invention that

2

it eliminates the aforementioned heating and cooling of insulating support members which heretofore had often resulted in distortion and misalignment of the elements of the gun structure, constituting a major problem.

5 In accordance with the foregoing and other objectives, the invention is characterized by provision of a hollow ceramic cylinder in which the metal parts of the gun structure are disposed. The ceramic cylinder includes means defining transversely extending apertures corresponding to locations of points of fixation of the gun parts thereto. According to the invention, irregularly shaped metal elements, such for example as studs, extend through the apertures and are spot welded in place to the metal gun parts. Each stud is so constructed and 10 arranged as to form a three point contact between the gun part and an aperture in the ceramic cylinder. When two or more portions of each metal gun part are secured by this method a permanent accurate alignment thereof is achieved by utilizing an annular space of but $\frac{1}{8}$ inch thickness or less.

15 In further accordance with the invention, the irregularly shaped metal studs are formed by slicing a metal rod at an angle with respect to a plane perpendicular to the axis of the rod. This angle of cut insures that when 20 a stud extends through an aperture, it engages the metallic gun part at one point for connection thereto and frictionally engages the ceramic cylinder wall at two points, thereby forming a three point supporting contact.

25 It is a feature of the invention, by way of comparison, that whereas electron gun structure heretofore held together by glass rods required a $1\frac{1}{8}$ inch diameter glass tube neck, the present invention permits use of a glass tube neck of but $\frac{3}{4}$ inch in diameter.

30 The reduction in diameter afforded by the invention is invaluable when it is considered that it meets the requirement that the turns of the coils forming the deflection yoke should be so disposed and configured as to be in close proximity to the electrons of the scanning beam. This arrangement ensures production of the highest possible magnetic field intensity and hence the application of a maximum deflecting force to the beam electrons emitted from the gun structure. In other words the invention enhances operation of the cathode-ray tube because the deflection yoke is able to operate with maximum efficiency.

35 The foregoing as well as other objects and advantages of the invention will best be understood upon consideration of the following description taken in light of the accompanying drawing, in which:

40 FIGURE 1 is an elevational showing, partly in section and with parts broken away, of a cathode ray tube embodying gun structure made in accordance with the invention;

45 FIGURE 2 is a somewhat enlarged fragmentary showing, partly in section, of the gun structure shown in FIGURE 1 and illustrating also techniques utilized in assembling same and characteristic of the invention in its method aspect; and

50 FIGURES 3 and 4 illustrate additional techniques of gun structure assembly which also characterize the invention in its method aspect.

55 With more particular reference to the drawing, and first to FIGURE 1 thereof, cathode ray tube 10 is provided with a generally cylindrical neck portion 11 having a flat end portion 12 through which electrically conductive terminal pins 13 extend.

60 Gun structure 14 made according to the invention is disposed within neck portion 11 and is supported from the left and right hand pins 13 as shown in FIGURE 1. Gun structure 14 comprises a cathode heater 15 disposed within an indirectly heated cathode sleeve 16 over the

end of which is disposed electron emissive material 20. Sleeve 16 is spaced relative to and supported within generally cylindrical control grid 21 by a suitable insulative disk 17 and a resilient washer 18 that frictionally engage the grid 21. The spacing of sleeve 16 is such that emissive material 20 is disposed adjacent a small opening 22 provided in a flat wall portion of the grid 21. Grid 21 is supported from pins 13, and as indicated above, cooperates with the latter to mount the gun structure within the neck portion 11. A generally cylindrical sleeve 23 of electrically insulative ceramic material is disposed in such a manner that its lower end portion partially encloses control grid 21. Sleeve 23 is supported by grid 21 through the agency of bracket means which comprises stud elements 24 that are affixed to grid 21 and extend into apertures 25, the latter extending through sleeve 23 generally transverse the axis thereof. The stud elements 24 are inclined with respect to and frictionally engage the walls of apertures 25 in the manner best seen in FIGURE 2 which illustrates the present inventive mode of frictional engagement of stud elements 24 with the ceramic sleeve.

In FIGURE 1, and in further accordance with constructional features of gun structure 14, generally cylindrical apertured screen grid 26 and a third grid 30 are supported in spaced relation as respects one another and concentrically with sleeve 23. Finally, the anode 31 is supported in like manner by additional stud elements 24 of the bracket means, which anode 31 comprises a combined getter ring 32 and snubber means 33 disposed in electrical contact with an electrically conductive coating (not shown) that extends over interior surface portions 34 of tube 10. Electrical connections of the above described components are made to the pin means 13 and to the conductive coating through means 33 by ribbon-like lead wires 37.

Additional important features of the invention will now be described with particular reference to FIGURES 2, 3, and 4. Irregularly shaped, prism-like bits of metal comprise stud elements 24 of the bracket means and are formed by slicing a cylindrical metal rod 24a (FIGURE 3) at an angle with respect to a plane perpendicular to the axis of the rod. An angular cut of 20° has been found satisfactory, which cut insures that when the stud element 24 is inserted into an upwardly presented aperture 25 (FIGURE 2) it will be so inclined therein as to engage the underlying grid at one point and the ceramic sleeve 23 at two points in a frictional, wedge-like manner.

The invention will be still more clearly understood from a description of the mode of assembly, in which connection it is seen in FIGURE 4 that the apertured cylinder 23 is clamped by set screw 36 in a fixture 35 having a mandrel portion 40 disposed for axial alignment with the cylinder. The diameter of portion 40 corresponds to the inside diameters of the cylindrical elements 26, 30 and 31 which have been positioned thereon in the desired spaced relation as respects one another and cylinder 23. Additional alignment of grid element 26 is provided by a central pin-like projection 41 of mandrel portion 40, said projection extending through the aperture in the element 26.

With the component elements assembled according to the showing of FIGURE 4, and with the apertures 25 preferably presented upwardly, stud elements 24 are inserted into apertures 25 as best seen in the enlarged showing afforded by FIGURE 2. With reference to FIGURE 2 it will be further appreciated that the stud elements also provide means for electrically connecting a lead wire 37 to a cylindrical gun component.

With stud elements 24 positioned so that they are inclined as shown in FIGURE 2, mild pressure is exerted on each such element by means of a resistance welding electrode as seen at 42 and a suitable current passed between the element 24 and the adjacent grid element 30 to weld the same together. Thus affixed to the grid ele-

ment, the stud elements will frictionally engage the walls of the apertures through which they extend whereby the attached grid element is accurately supported. Connection of a lead wire 37 to a stud element is achieved by applying the welding electrode to wire 37 in the position shown in FIGURE 2 and again passing a suitable welding current between the wire and the stud element. The welding electrode and suitable circuitry are conventional, and are shown only diagrammatically in FIGURE 2 as comprising a voltage source L, an energizing switch S, transformer means T, and the lead wire connections required to effect the welding current flow. After welding the upwardly presented stud elements 24, the fixture 35 is rotated 180° about its axis to present the remaining apertures 25 upwardly and the stud insertion and welding operation is repeated as described above. It will be understood that the invention contemplates use of any desired number of supporting stud elements, and is not limited to the number or the precise shape shown.

It will further be understood that a similar operation is carried out in attaching the control grid 21 to sleeve 23, whereupon final attachment of the remaining gun structure elements is made as shown in FIGURE 1.

The invention is featured by its simplicity of construction and ease of assembly, particularly when considered in light of the fact that the openings 25 need not provide a close size match with the stud elements 24. Moreover, tolerances capable of being maintained in fabrication of ceramic elements of this type are not conducive to providing a uniform close size match, and this problem is readily overcome by the invention.

While but a single embodiment of the invention has been described, it will be understood that the invention is susceptible to modification, as is contemplated by the scope of the appended claims.

I claim:

1. In electron gun structure: a tubular electrode; a tubular member of electrically non-conductive material enclosing said electrode and having a common axis therewith; means defining a plurality of apertures extending transversely through said tubular member; and electrode supporting bracket means affixed to said tubular electrode, said bracket means comprising a plurality of rod elements each extending into an associated one of said apertures and each inclined as respects the major axis of its associated aperture and having portions of substantially lesser cross sectional area than said apertures, an end portion of each said inclined rod element being affixed to said electrode and oppositely disposed axially spaced lateral portions thereof disposed in frictional electrode supporting engagement with walls of said apertures.

2. Gun structure according to claim 1 characterized in that said tubular member is of a ceramic material.

3. In electron gun structure: tubular electrode means; an elongated electrically non-conductive member disposed adjacent said electrode means and having apertures extending transversely thereof and through said non-conductive member; and electrode supporting bracket means comprising rod-like elements each of substantially less cross-sectional area than and extending into an associated one of said apertures, each said element having a pair of oppositely disposed parallel face portions inclined as respects the major axis of said element, the construction and arrangement being such that engagement of a recited angular face portion with said electrode effects inclined positioning of each said rod-like element within an aperture, as respects the major axis thereof, whereby an element engages opposite, axially spaced sides of an associated aperture frictionally to retain the electrode means in the recited supported relation.

4. In electron gun structure: tubular electrode means; elongated electrically non-conductive insulative means disposed adjacent said electrode means and having apertures extending therethrough transversely of said tubular

electrode means; and electrode supporting brackets comprising irregularly shaped pieces of metal welded to said electrode means and having portions frictionally engaging both the edge and an opposite portion of the inside surfaces of the material defining said apertures.

5. In electron gun structure: electrode means; electrically non-conductive insulative means disposed adjacent said electrode means and having apertures extending therethrough transversely of said electrode means; and electrode supporting brackets comprising irregularly shaped pieces of metal welded to said electrode means and having portions frictionally engaging both the edge and an opposite portion of the inside surfaces of the material defining said apertures.

6. In electron gun structure: means defining a tubular electrode; a tubular member of electrically non-conductive material enclosing said electrode and having a common axis therewith; means defining a plurality of apertures extending transversely of and through said tubular member; and electrode supporting bracket means affixed to said tubular electrode, said bracket means comprising a plurality of rod-like elements each extending into one of said apertures and having a pair of oppositely disposed parallel face portions positioned with angularity as respects its axis, the construction and arrangement being such that supporting engagement of a recited angular face portion with said electrode effects inclined positioning of each said rod-like element within an aperture whereby such an element engages opposed, axially spaced sides of the aperture to retain the electrode means in the recited supported relation.

7. Gun structure according to claim 6 and further characterized in that each said rod element comprises a cylindrical section and said face portions comprise generally elliptical surfaces.

5. In electron gun structure: electrode means; electrically insulative means disposed adjacent said electrode means and having apertures extending therethrough transversely of said electrode means; and electrode means supporting brackets comprising rod-like elements each of substantially less cross-sectional area than an associated aperture and extending into the associated one of said apertures, said elements each having at least a transverse face portion positioned with angularity as respects the axis of the element, the construction and arrangement 10 being such that supporting engagement of a recited angular face portion with said electrode means effects inclined positioning of the rod-like element within the associated one of said apertures, as respects the major axis thereof whereby the element engages sides of the associated 15 aperture frictionally to retain the electrode means in the recited supported relation.
